COMBINED PENCIL WELL AND SHARPENER

Jack Fairchild Fleming, Boonton, N.J., assignor to Sterling Plastics Co., Mountainside, N.J., a corporation of New Jersey

Filed Sept. 11, 1969, Ser. No. 19,113

Term of patent 7 years

Int. Cl. D19—02

U.S. Cl. D74—5

FIG. 1

FIG. 5

FIG. 4

FIG. 2

FIG. 3

FIG. 1 is a top plan view of a combined pencil well and sharpener embodying my new design;

FIG. 2 is a front elevational view thereof;

FIG. 3 is a an elevational view of one side thereof;

FIG. 4 is an elevational view of the opposite side thereof; and

FIG. 5 is a perspective view of an upper portion thereof, looking into the pencil compartment and toward the chamber for collecting shavings from the pencil sharpener.

I claim:

The ornamental design for a combined pencil well and sharpener, substantially as shown and described.
